UNITED STATES PATENT OFFICE.

JESSE PERKINS MILLER, OF HOUma, LOUISIANA, ASSIGNOR OF ONE-HALF TO J. H. THATCHER, OF HOUma, LOUISIANA.

EXPANSIVE DRILL BIT FOR CABLE TOOLS AND THE LIKE.

Application filed August 5, 1922. Serial No. 579,851.

My invention relates to improvements in well drills and it consists of the constructions, combinations and mode of operation herein described and claimed.

5 An object of the invention is to provide a bit for cable tools designed in such a manner that it will pass through a casing and have the capability of opening beyond the end of the casing and drill a hole large enough for 10 said casing to freely follow.

Another object of the invention is to provide a bit which may be operated as an underreamer which will ream a hole already drilled under a casing to such size that the 15 casing will freely pass.

A further object of the invention is to provide an underreamer which will enlarge the hole already made in the productive stratum and thus cause the well to produce 20 more oil, gas, etc.

A further object of the invention is to provide an underreamer which will enlarge the bottom of the oil well so that it will hold more detritus and therefore require cleaning 25 at less frequent intervals.

A further object of the invention is to provide an underreamer of such rigid construction that fishing operations are reduced to a minimum.

30 Other objects and advantages will appear in the following specification, reference being had to the accompanying drawings, in which:

Fig. 1 is a longitudinal sectional view illustrating the arrangement of the expansive drill bit, the blades being closed as in lowering the bit,

35 Fig. 2 is a view similar to Fig. 1, the blades being extended or opened as in the cutting operation,

40 Fig. 3 is a detail cross section on the line 3—3 of Fig. 2, showing the blade-retaining pins,

45 Fig. 4 is a section of the blade taken on the same plane as the line 3—3 of Fig. 2,

Fig. 5 is a cross section on the line 5—5 of Fig. 2,

50 Fig. 6 is a detail perspective view of one of the blades,

55 Fig. 7 is a longitudinal section of a slight modification of the expansive drill bit, illustrating the use of a spring lifting device in substitution of the hydraulic lifting device in Figs. 1 and 2,

Fig. 8 is a side elevation of a form of blade

which is cut away in such a manner as to enable performing underreaming operations,

Fig. 9 is a side elevation of another form of blade which is thickened to provide a broad-bladed underreamer,

60 Figure 10 is a detail cross section on the line 10—10 of Figure 9.

The invention disclosed in this application is an improvement on the drill bit disclosed in my co-pending application filed August 3, 1921, Serial No. 489,522 which has since become Patent No. 1,448,762, issued March 20, 1923. The expansive drill bit of that application is more particularly adapted for use in connection with rotary drilling tools, 65 whereas the expansive drill bit of this application is more particularly adapted for cable drilling and underreaming. The blades 1 and 2 are opened by being raised into the bit body 3. As one blade is identical 70 with the other, the description of one will suffice for both.

Attention is directed to Fig. 6 which illustrates the blade 1 as an example. The shank 4 is of semi-circular formation so that when the two blades are fitted together (Fig. 4) the completed shank appears round in cross section. The shank gradually enlarges downwardly from the head 5 until it meets the shoulder 6, the eccentric shape of which arises as a natural consequence of the formation of the blade 1.

As shown in Fig. 5, the blade 1 (also the blade 2) is considerably thicker at its outer periphery or cutting edge than at the inner edge. The curvatures 7 and 8, which respectively represent the outer and inner edges of the blade, are struck on the arcs of a circle the diameter of which would embrace both blades when closed as in Fig. 1. 90 This being so, the reader will doubtless inquire why the shoulders 6 should present the appearance of parts of an eccentric as in Figs. 4 and 6.

Reference to Figs. 1 and 2 will disclose 100 the axial lines 9 and 10 of the shanks 4 of the blades to extend in directions different from the axial lines 11 and 12 of the blades 1 and 2, there being a definite reason for this formation.

When the blades 1 and 2 are down and closed as in Fig. 1, the axial lines 11 and 12 of the blades coincide with each other and with the axis of the bit body 3. The axial lines 9 and 10 of the shanks 4, however, form 105 110

angles with each other and with the axial line of the bit body 3. As the bit shanks 4 are raised into the bit body their axial lines 9 and 10 are forced to coincide with each other and with the axial line of the bit body, and naturally the axial lines 11 and 12 of the blades will then form angles with each other because the forced engagement of the conical base portion 13 of the shank with the conical entrance 14 to the opening 15 of the bit body causes the shanks to meet, but the blades 1 and 2 to spread apart. This explains the reason for the diverse axial lines of the shank, and also explains the manner in which the blades are opened when moved inwardly in respect to the bit body.

Each head 5 has a recess 14^a, the two of which when fitted together define a pocket or chamber intended to be occupied by the boss 15^a of the piston rod 16. Connection of the piston rod is made with the head by a pin 17 which passes through transversely of the chamber 14^a and occupies holes 18 in the sides of the two heads 5.

At a place a short distance below the chamber 14 each shank is cut out at the sides at 19 to define spaces for the retaining pins 20 which limit the vertical movement of the bit by virtue of the engagement of the shoulders 21 provided by the formation of the spaces 19. When the bit is closed as in Figure 1, the shoulders 21 engage the retaining pins and thus limit the outward movement of the bit. When the bit is opened as in Fig. 2, the conical base portion 13 of the shank fits tight in the conical entrance 14 to the opening 15 of the bit body. Shoulders 6 rest against the lower end of the bit body and the inward movement of the bit is thus limited.

The hydraulic lifting device in Figs. 1 and 2 comprises a cylinder 23 into which the piston rod 16 extends. The lower end of the lifting cylinder is closed by a cap 24 through which the rod 16 passes and which carries a packing 25 for the obvious purpose of making a tight joint between the movable piston rod and the lifting cylinder.

The upper end of the piston rod carries a piston 26, and situated between the piston and the lower end of the cylinder is a lifting spring 27, the function of which is to retard the up and down movements of the bit when the bit body 3 is moved up and down initially for the purpose of spreading the blades into the cutting position. Mounted above the piston 26 and forming a part thereof is a casing 28 which serves the function of a valve cage in that it carries the inwardly opening fluid valve 29 and outwardly opening or exhaust valve 30.

A spring 31 keeps the inlet valve 29 closed, and a more powerful spring 32 keeps the outlet valve 30 closed. The lifting cylinder 23 is relatively stationary because it is

mounted upon a supporting pin 33 which passes through the bit body and also through a plug 34 in the upper end of the cylinder. As is usually the case, the bit body terminates in a threaded pin 35 through which connection is made with the cable.

The operation of the hydraulic lifting device is as follows: The drilling tool is lowered through the casing into the well with the blades 1 and 2 of the bit extended as in Fig. 1. That is to say, they are extended in respect to the bit body 3 and are hanging down in the closed position. It is necessary to spread the blades 1 and 2 into the position in Fig. 2 before the drilling can commence. It is here that the function of the lifting device in the bore 15 of the bit body enters. Bear in mind that the lifting device is supported in the bore 15 by the supporting pin 33 and while most of the weight of the bit blades 1 and 2 is supported by the retaining pins 20 (by virtue of the engagement of the shoulders 21) yet a part of the weight of the bit is supported by the spring 27 due to the engagement thereof with the piston 26. While being handled at ordinary speeds (as going into the hole) the blades 1 and 2 stay down as in Fig. 1, dividing their weight between the retaining pins 20 and the spring 27, as just stated.

Upon reaching the scene of the cutting operation, the bit body 3 should be worked up and down by a few rapid strokes so that the fluid F above the piston 26 is worked down through the inlet valve 29 beneath the piston 26, causing the progressive raising of the piston in respect to the lifting cylinder 23 and consequently the raising of the bit blades until the conical shank 13 engages the conical opening 14 in the end of the bit body and the blades assume the spread position in Fig. 2. The blades are raised and spread step by step by a non-retrograde action, being positively prevented from moving backwards when each step is accomplished. Of necessity, the piston 26 must have openings through which the fluid may pass from above to the space below.

Now consider the manner in which the fluid is transferred as stated. As the walking beam of the drilling apparatus on the surface drops the stem and bit, the natural expansive force of the compressed spring 27 tends to slacken the downward speed of the blades by virtue of its pressing up underneath the piston 26. In other words, the spring 27 tends to slacken the downward movement of the bit. The resultant upward relative movement of the piston 26 in the lifting cylinder 23 causes the valve 29 to open and permit some of the fluid above the piston to flow into the space beneath the piston 26. When the relative movement of the bit body ceases, the valve 29 again closes.

When the aforesaid walking beam nears the top of its upward stroke, the bit body 3 and blades 1 and 2 will be found to rise together but the blades being supported by the expansive spring 27 will not slow down as readily or rapidly as the bit body does, and again the result is a rising of the piston 26 in the lifting cylinder 23. Again, fluid will pass down through the valve 29 and it will be found that only a few strokes are required to force enough fluid beneath the piston 26 to cause the proper elevation of the blades in respect to the bit body. Should it so happen that the reamed hole at the bottom of the well is deep enough, the foregoing results may be obtained (i. e. the blades may be opened) by dropping the tool a short distance and merely catching the cable several times by applying the brake. This produces a succession of jerks which have the effect of intermittently opening the valve 29 so that the fluid is led beneath the piston 26.

When the bit is used to drill, or when a hole to be reamed is smaller than the bit when closed, the bit blades may be opened by merely resting them on top of the small hole, whereupon the bit body 3 will move down around the bit and cause the shanks 30 of the blades to ride up into the bore. When pulling the bit out of the hole, the holders 6 of the blades will catch under the casing and pull the piston rod 16 and piston 26 down against the tension of the spring 27. The resulting pressure against the outlet valve 30 will cause that valve to open against the tension of the spring 32 so that the fluid again passes up into the space above the piston. The reader might inquire 40 why the outlet valve 30 does not open when pressure is imposed on the fluid after it passes through the inlet valve 29. As stated before, the closing spring 32 is considerably stronger than the spring 31 of the inlet valve, and sufficiently strong to hold the outlet valve closed under normal operating circumstances.

The spring lifting device in Fig. 7 constitutes a different construction but is intended to accomplish the same purpose as that of the hydraulic lifting device, namely, to extend the bit to an operative position. The cylinder 23^a corresponds to the lifting cylinder 23 in Fig. 1. A plug 34^a closes the upper end of the cylinder, provides a means for mounting the lifting cylinder on a pin similar to the pin 33 in Fig. 1 and serves as supporting means for a pair of springs 36 and 37, the latter of which is stronger than the former. Being of the same dimensions the lifting cylinder 23^a may be used interchangeably with the hydraulic lifting cylinder 23 in the bore 15 of the bit body 3.

The spring 36 is suitably attached to and therefore supports a lifting link 38 which

has a recess 39 adapted to receive the head 40 of a latch 41 which is supported by the other and stronger spring 37. The lifting link has shoulders 42 adapted to engage the lower edge of the cylinder 23^a when the bit 70 is drawn up and assumes the open position. On a somewhat similar principle, the head 40 has shoulders 43 and 44, the former to normally engage the edge of the cylinder, the latter to engage the heel 45 at the upper 75 end of the recess 39. The bottom of the recess is beveled at 46 to be engaged by a corresponding bevel 47 on the head of the latch. The bevel 46 is intended to force the latch 40 into the recess 39.

The operation of the spring lifting device is as follows: The lifting link 38 terminates in a head 48 and this head is provided with a hole to receive a bit pin 17^a corresponding to the pin 17 in Fig. 1, for the obvious purpose of supporting the heads 5^a of a pair of blades which may be of the form disclosed in Fig. 1 or of either of the forms disclosed in Figs. 8 and 9. The spring 36 (like spring 27 in Fig. 1) supports part of the weight of 90 the bit, the other part being supported by the retaining pins.

Normally the blades are held down by their own weight and remain closed. They even remain closed at ordinary lowering speeds and will pass through any casing through which the bit body itself is passing. One quick up and down motion of the tool will result in such a reaction of the spring 36 that the lifting link 38 will move up far 100 enough to bring its recess 39 adjacent to the head 40 of the latch. Engagement of the bevels 46 and 47 will cause the shoulder 44 of the latch to ride beneath the heel of the lifting link and bring the two into engagement with a snap. The stronger spring 37 now augments the spring 36 and the two pull the bit upwardly in respect to the cylinder 23^a until the bit blades are seated in bit body.

It seems an obvious expedient to use either expansion or compression springs in either of the foregoing types of lifting devices. The underlying reason for the opening of the bit in either modification is very readily understood when one stops to consider that all freely falling objects move at the same rate. If one is retarded with respect to another, naturally the retarded object falls slower. In the two forms of the invention the springs retard the fall of the bit blades and in fact accelerate the fall of the tools and bit body in respect to the blades.

When the tools with the bit body are dropped by the walking beam on the surface, the blades falling slower than the bit body rise up into the cone-shaped opening 14 (Figs. 1 and 2). Also, when the tools are lifted, their momentum carries them a distance against gravity. All objects thrown 125

at equal velocity will rise to the same height against gravity, but according to the invention, the springs assist the blades to rise faster than the other parts of the bit, thus 5 in effect retarding the tools and bit body. Since the blades rise higher than the bit body, it follows that but a few strokes of the beam at the top are required to raise and open the bit.

10 The modifications in Figs. 8 and 9 are intended to disclose various types of bit blades which may be used in connection with the lifting devices. In Fig. 8, the lower end of the blade 1^b is cut away at an angle as 15 at 49 so as to make an underreamer blade out of an ordinary bit blade which formerly included a portion indicated by the dotted lines. In Fig. 9, the blade 1^c is cut away at 50 and thickened at 51 to make an underreamer blade of a very sturdy construction. The cut away portion 50 makes a hollow underreamer of the blade 1^c.

While the construction and arrangement of the improved expansive drill bit as herein 25 described and claimed is that of a generally preferred form, obviously modifications and changes may be made without departing from the spirit and scope of the invention as claimed.

30 I claim:—

1. In drilling apparatus, a drill having expansive elements, and means for expanding said elements step by step to a permanent operative position by a series of up and down 35 motions imparted to the drill.

2. In drilling apparatus, a drill having expansive elements, means operable to produce a non-retrograde expanding action of said elements to a permanent operative position by a series of up and down movements imparted to the drill after the drill 40 has passed the end of a casing through which it is adapted to be lowered but before the bottom of the bore is reached, and means to hold said elements in said operative position.

45 3. In combination with means by which a tool is lowered into a well, a tool carried by said means comprising a bit body, expansive blades carried by said body, and means 50 operated by successively lowering the cable and dropping the tool in the well then suddenly holding the cable and stopping the tool thereby to move the blades into and sustain them in an expanded and operative position 55 on the bit body.

60 4. A bit body having expansive blades, a lifting cylinder containing fluid and occupying a bore in the bit body, means by which the cylinder is supported in the bore, retaining pins by which part of the weight 65 of the blades is supported while in the closed position, means extending from the blades into said cylinder, resilient means having such engagement both with a part of said 70 extending means and with the cylinder to

furnish the remainder of the support for the blades while in said closed position, and means which act upon the fluid during a series of up and down movements of the bit body to hold the blades in the expanded and 75 operative position to which they are moved by said movements.

5. A well drill comprising a bit body, expansive blades carried thereby, means which exercises a supporting function for the 80 blades, resilient means in connection with a part of said supporting means to assist said function, and means in connection with said supporting means causing the transfer of fluid thereunder by virtue of a series of up and down movements of the drill to cause the supporting means to move inwardly in respect to the drill body and shift the blades to an expanded position.

6. A well drill comprising a bit body, a chamber by which a fluid is contained, expansive blades carried by means which extends into said chamber, resilient means in connection with said carrying means to exercise a supporting function therefor, and means in connection with said carrying means adapted to transfer fluid from the space above to a space below a part of said carrying means to cause the lifting thereof and the moving of the blades to an expanded 85 position.

7. A well drill comprising a bit body having expansive blades, a rod in connection with the blades having a spring which partly supports the weight of the blades, a fluid chamber, and a piston on the rod having valve mechanism to transfer the fluid under the piston under compression by virtue of the initial up and down movement of the drill to lift the blades in respect to the 90 bit body and hold them in the expanded and operative position.

8. A well drill comprising a bit body having a bore, a fluid cylinder suspended in said bore, expansive blades carried by a rod having a piston occupying said cylinder, a spring disposed under the piston to exercise a supporting function for the blades, and a valve mechanism embodied in the piston adapted to transfer fluid from the cylinder 105 under the piston by the action of a series of up and down movements of the drill to raise the piston and blades in respect to the bit body and lock them in the expanded position during operation.

9. A well drill comprising a bit body having a bore, a fluid cylinder suspended in said bore, expansive blades carried by a rod having a piston occupying said cylinder, a spring disposed under the piston to exercise 110 a supporting function for the blades, a valve mechanism embodied in the piston adapted to transfer fluid from the cylinder under the piston by the action of a series of up and down movements of the drill to raise the 115 cylinder to lock the blades in the expanded position.

5 piston and blades in respect to the bit body and lock them in the expanded position during operation, and a valve embodied in said valve mechanism enabling the re-transfer-
ence of the fluid above the piston when the blades, rod and piston are bodily pulled out by catching the former on the well casing in withdrawing the drill.

10. An underreamer comprising a bit body, expansive blades normally closed and ex-
tended in respect to the body, a compressed
spring having connection with supporting
means of the blades to retard the action of
gravity on the blades when the bit body is
15 lowered, and valve mechanism adapted to
transfer fluid to a place beneath said sup-
porting means at each retarding action of
the spring during a series of up and down
movements of the bit body, to cause the
20 elevation of the blades in respect to the bit
body and the expansion thereof to an opera-
tive position.

11. A well drill comprising a bit body
having a bore with a conical outlet, expan-
sive blades having conical shanks situated in
25 said outlet, and instrumentalities in said
bore including means for raising the blades
in respect to the bit body upon performance
of a series of up and down motions thereof,
30 and other means to sustain the blades at each
raising movement and finally cause said
conical shanks to align with the conical out-
let and thereby expand the blades to an
operative position.

35. 12. A drill comprising a bit body adapted
to be supported, expansive bits carried by
and hanging loose from the body when
closed, and means reacting upon being sub-
jected to a succession of impulses imparted
40 thereto by said support to draw the bits up
and means to sustain the bits after each re-
action finally holding them in engagement
with the body.

13. A drill comprising a bit body adapted
45 to be supported, expansive bits carried by and
hanging loose from the body when closed, a
fluid-filled cylinder in the body, a rod con-
nected to the bits extending into the cylinder
where it has a piston with a valve, and a
50 spring which presses up under the piston
and is adapted to supplement the inertia of
the piston, rod, and bits upon either an up
or down impulse of the bit body by a sudden
stopping of the support to thereby cause the
55 valve to open and pass fluid under the piston
to raise the bits until they contact the body.

14. A drill comprising a bit body adapted
to be supported, expansive bits carried by
and hanging loose from the body when

closed, a fluid-filled cylinder in the body, a 60
rod connected to the bits extending into the
cylinder where it has a piston with a valve,
a spring which presses up under the piston
and is adapted to supplement the inertia of
the piston, rod, and bits upon either an up 65
or down impulse of the bit body by a sudden
stopping of the support to thereby cause the
valve to open and pass fluid under the piston
to raise the bits until they contact the body,
and another valve in the piston opening op- 70
positely to the first valve being adapted to
let the fluid pass back up when the bits are
hooked under a casing in withdrawing the
drill.

15. Apparatus of the character described 75
comprising a freely up and down movable
body, a cutting member, yieldable means
supplying a partial support for the cutting
member on the body and producing an ac-
celeration of the cutting member different 80
from that of said body, and liquid means
checking movement of said cutting member
in one direction at the end of each ac-
celerated movement.

16. In drilling apparatus, a drill having 85
expansive elements, and fluid means embod-
ied in the drill for expanding said elements,
step by step to a permanent operative pos-
ition by a series of up and down motions im-
parted to the drill.

17. A drill comprising a bit body adapted
to be supported, expansive bits carried by
and hanging loose from the body when
closed, and means reacting upon being sub-
jected to a succession of impulses imparted
95 thereto by said support to draw the bits up
step by step, and means to sustain the bits
after each reaction, said bits and adjacent
parts of the body being so shaped as to ex-
pand the bits as they are raised. 100

18. In drilling apparatus, a body having
cutting elements, means which is movable
relatively to said body and from which said
elements are suspended, said means having a
piston, means containing a fluid into which
95 said relatively movable means and piston
extend, and valve means incorporated in the
piston permitting such transfer of fluid
through the piston as will move the cutting
elements in one direction step by step and 110
hold them in position at the end of each
step.

19. Apparatus of the character described
comprising expansive elements, and means
requiring an up and down motion of the 115
apparatus to expand said elements to an op-
erative position.

JESSE PERKINS MILLER.
